[57] CLAIM

The ornamental design for an exterior shell of a vehicle roof, as shown and described.

DESCRIPTION

FIG. 1 is a left, front perspective view of an exterior shell of a vehicle roof showing our new design;

FIG. 2 is a left side elevation view thereof;

FIG. 3 is a right side elevation view thereof;

FIG. 4 is a front elevation view thereof;

FIG. 5 is a top plan view thereof;

FIG. 6 is a left, front perspective view of an exterior shell of a vehicle roof of an exterior shell of a vehicle hood showing a second embodiment of our new design;

FIG. 7 is a left side elevation view of the embodiment of FIG. 6;

FIG. 8 is a right side elevation view of the embodiment of FIG. 6;

FIG. 9 is a front elevation view of the embodiment of FIG. 6;

FIG. 10 is a top plan view of the embodiment of FIG. 6;

FIG. 11 is a left, front perspective view of an exterior shell of a vehicle roof of an exterior shell of a vehicle hood showing a third embodiment of our new design;

FIG. 12 is a left side elevation view of the embodiment of FIG. 11;

FIG. 13 is a right side elevation view of the embodiment of FIG. 11;

FIG. 14 is a front elevation view of the embodiment of FIG. 11; and,

FIG. 15 is a top plan view of the embodiment of FIG. 11. The broken lines shown on the various FIGS. are for illustrative purposes only and form no part of the claimed design.
